UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 28,954, dated June 28, 1898.

Application filed May 17, 1898. Serial No. 680,990. Term of patent 7 years.

To all whom it may concern:

Be it known that I, JOHN P. ODGERS, a citizen of the United States, residing in Philadelphia, Pennsylvania, have invented a new and original Design for a Card-Mount, of which the following is a specification.

- My design is fully shown in the accompanying drawing, which represents a face view of the card-mount.
- 10 The essential features of the design consist of the card-mount having the rectangular border located some distance inwardly from the edge of the card and consisting of a vine-like figure comprising a serpentine stem, with leaves and buds or blossoms projecting therefrom at intervals, said buds be-
- 15

ing arranged in pairs and the stem of the vine forming curves on substantially the same radius at the corners of the border.

In the drawing, 1 represents said serpentine 20 stem, 2 the projecting leaves, and 3 the projecting buds or blossoms.

I claim—

The design for a card-mount, substantially as shown and described.

In testimony whereof I have signed my name to this specification in the presence of two subscribing witnesses.

JOHN P. ODGERS.
